Wm C. Harris Inventor

A. Robert Roseman

Hubbil B. Hutchins

United States Patent Office.

WILLIAM C. HARRIS, A. ROBERT ROSEMAN, AND HUBBIL B. HUTCHINS,
OF PHILADELPHIA, PENNSYLVANIA.

Letters Patent No. 74,530, dated February 18, 1868.

IMPROVEMENT IN CARRIAGES FOR ADVERTISING.

The Schedule referred to in these Letters Patent and making part of the same.

TO ALL WHOM IT MAY CONCERN:

Be it known that we, WILLIAM C. HARRIS, A. ROBERT ROSEMAN, and HUBBIL B. HUTCHINS, of the city of Philadelphia, in the State of Pennsylvania, have invented a new and useful Improvement in Panoramic Advertising-Carriages; and we do hereby declare that the following is a full, clear, and exact description of the construction and operation of the same, reference being had to the accompanying drawings, making a part of this specification, in which—

Figure 1 is a perspective view of one of the said improved carriages, and

Figure 2 a plane view of the same, having its roof or cover removed therefrom—

Like letters of reference indicating the same parts when in both figures.

The nature of our invention consists substantially, as hereinafter described, in the combined arrangement of a long, semi-transparent band or canvas curtain with advertisements thereon, and being adapted for being easily moved by the driver around the outside of a large supporting-skeleton-frame on wheels, so that it can be drawn or driven through the streets of a town, and having also within it lamps for illuminating the canvas band, so that the series of advertisements thereon may be successively and distinctly displayed, either at night or in the day-time.

Referring to the drawings, A B is the frame or body of the carriage, and C the panoramic or travelling-band, with sundry advertisements thereon. The frame A B has a close bottom or platform, *a*, which rests upon ordinary wheels, (indicated by the faint lines *v v*.) and supports, by means of fixed posts, *b' b'*, a semi-transparent roof or cover, *a'*. Near each corner of the frame A B there is a vertical friction-roller, *b''*, and also two, *b''' b'''*, near the middle of the front end of the frame A B, in contact with which six rollers the panoramic band C is supported and moved. The two ends of the band C are fastened respectively to two vertical rollers, *b⁴ b⁴*, arranged within the frame, or near its front end, so that the said band C can be taken up and given out by them alternately as it is drawn by one of them around the outside of the car or carriage in contact with the friction-rollers *b'' b'''*. The rollers *b⁴ b⁴* are each connected, by means of a grooved pulley, *d*, on its upper end, and a cord, *e*, to a grooved pulley, *f*, near each side of the driver's seat, and to each of these latter pulleys *f f* a knob-handle, *g*, is attached, so that the driver can thereby cause either of the rollers *b⁴ b⁴* to rotate and wind around it the band C, thus drawing it from the one roller *b⁴* to the other, around the outside of the frame A B, in contact with the friction-rollers *b'' b'''*.

The band C is made of muslin, or other suitable semi-transparent fabric, and has the various advertisements or show-cards painted on or attached thereto, so as to be readily seen and read or understood by the public as the carriage is drawn through the streets. The roof or cover *a'* is also made of a semi-transparent fabric, and the advertisements painted on or attached in the same manner and for the same purpose.

Within the frame or body A B, two or more lamps, *h h*, are secured, and lighted at night, so that the whole of the advertisements which may be on the roof, and successively those on the sides and ends of the carriage, can be illuminated thereby, and distinctly read or understood at night.

The movement of the band C is effected by the driver, who, taking hold of the knob *g* of one of the pulleys *f f*, and rotating the latter, thus causes the roller *b⁴* with which it is connected to draw the band C gradually off of the opposite roller *b⁴* and around the frame A B; and when the band C has thus been unwound from one roller *b⁴*, he operates the other pulley *f* in the same manner, and thus transfers the band C back to the other roller.

It will be seen that this panoramic advertising-carriage will give a more public and varied display of advertisements than any other device of the class heretofore made for the purpose.

We are aware that small panoramic advertising-cases or boxes have been made and put into hotels and cars, and that stationary advertisements have been exhibited upon the opaque sides and ends of cars and carriages, and also upon illuminated portable banners or lanterns; therefore we do not desire to claim either of these devices; but having fully described our improvement,

What we claim as our invention, and desire to secure by Letters Patent is confined to the following, viz:

We claim a large-skeleton frame, having lamps enclosed therein, and being supported on wheels or runners,

so that it can be drawn or driven like a carriage or car through the streets of a town, and having also a long semi-transparent advertising-band or canvas curtain arranged around the outside of the said frame, so that it can be moved by the driver as a panoramic curtain, the whole being constructed, arranged, and operated as herein described and set forth, for the purpose specified.

WM. C. HARRIS,
A. ROBERT ROSEMAN,
HUBBIL B. HUTCHINS.
